(57) **CLAIM**

The ornamental design for a remote control vehicle chassis adapter as shown and described.

DESCRIPTION

FIG. 1 is a perspective view of an embodiment of a remote control vehicle chassis adapter.

FIG. 2 is a front elevation view of the remote control vehicle chassis adapter of FIG. 1.

FIG. 3 is a rear elevation view of the remote control vehicle chassis adapter of FIG. 1.

FIG. 4 is a left elevation view of the remote control vehicle chassis adapter of FIG. 1.

FIG. 5 is a right elevation view of the remote control vehicle chassis adapter of FIG. 1.

FIG. 6 is a top elevation view of the remote control vehicle chassis adapter of FIG. 1.

FIG. 7 is a bottom elevation view of the remote control vehicle chassis adapter of FIG. 1.

FIG. 8 is a perspective view of the remote control vehicle chassis adapter of FIG. 1.

FIG. 9 is a perspective view of the remote control vehicle chassis adapter of FIG. 1.

FIG. 10 is a perspective view of the remote control vehicle chassis adapter of FIG. 1; and,

FIG. 11 is a perspective view of the remote control vehicle chassis adapter of FIG. 1.

In FIGS. 8-11, broken lines illustrate environmental structures and form no part of the claimed design.
